(57) **CLAIM**

The ornamental design for a vehicle headlight, as shown and described.

DESCRIPTION

FIG. 1 is a perspective view of a vehicle headlight showing our new design;

FIG. 2 is a side elevational view thereof;

FIG. 3 is a front elevational view thereof;

FIG. 4 is a perspective view of a right-handed version thereof;

FIG. 5 is a side elevational view of a right-handed version thereof;

FIG. 6 is a front elevational view of a right-handed version thereof; and,

FIG. 7 is a frontal perspective view of the headlights of FIGS. 1-6 as they would appear on a vehicle.

The broken line showings of the surrounding vehicle front end area in FIGS. 1-6, and the remainder of the vehicle in FIG. 7 are for illustrative purposes only and form no part of the claimed design.
